UNITED STATES PATENT OFFICE

147,725

DESIGN FOR A HAMPER OR SIMILAR ARTICLE

Harold Gleitsman, New Rochelle, N. Y.

Application August 29, 1945, Serial No. 121,725

Term of patent 14 years

(Cl. D58—4)

To all whom it may concern:

Be it known that I, Harold Gleitsman, a citizen of the United States of America, residing at New Rochelle, Westchester County, New York, have invented a new, original, and ornamental Design for a Hamper or Similar Article, of which the following is a specification, reference being had to the accompanying drawing, forming a part thereof.

Fig. 1 is a perspective view of a hamper showing my new design.

Fig. 2 is a front elevational view thereof.

Fig. 3 is a fragmentary sectional view taken substantially on the line 3—3 of Fig. 2 and looking in the direction of the arrows.

Fig. 4 is a sectional view taken substantially on the line 4—4 of Fig. 2 and looking in the direction of the arrows.

The dominant features of my design reside in the portions shown in full lines in Figs. 1 and 2.

I claim:

The ornamental design for a hamper or similar article, as shown and described.

HAROLD GLEITSMAN.
